(57) **CLAIM**

The ornamental design for a motor vehicle body as shown and described.

DESCRIPTION

FIG. 1 is an enlarged front elevational view of a motor vehicle body showing my new design;

FIG. 2 is an enlarged rear elevational view thereof;

FIG. 3 is a left side elevational view thereof;

FIG. 4 is a right side elevational view thereof;

FIG. 5 is a top plan view thereof;

FIG. 6 is a top, front and left side perspective view thereof; and,

FIG. 7 is a top, rear and left side perspective view thereof. The broken lines shown throughout the drawing views are for illustrative and environmental purposes and represent some boundaries that form no part of the claimed design.
